UNITED STATES PATENT OFFICE.

BARCLAY WHITE, OF LANSDOWNE, PENNSYLVANIA.

SUPPORTING, SPACING, AND REINFORCING MEANS FOR CONCRETE CONSTRUCTION.

1,108,647.

Specification of Letters Patent. Patented Aug. 25, 1914.

Application filed July 31, 1911. Serial No. 641,624.

To all whom it may concern:

Be it known that I, BARCLAY WHITE, a citizen of the United States, and a resident of Lansdowne, Delaware county, Pennsylvania, have invented certain Improvements in Supporting, Spacing, and Reinforcing Means for Concrete Construction, of which the following is a specification.

My invention relates to reinforcing means for concrete construction of floors, walls, ceilings, slabs, &c., and the object of my invention is to provide means for supporting and spacing in their proper position the reinforcing rods employed in such concrete construction, and by the same means furnishing reinforcement in a direction approximately at right angles to the supported and spaced rods.

A further object of my invention is to provide retaining means for securing the reinforcing rods to the supporting and spacing means to prevent dislodgment or separation at the crossing point, and a still further object is to provide locking means for the rod retaining means.

The reinforcing, supporting and spacing means forming the subject of my invention comprises a strip or bar of metal having integral supporting elements struck up therefrom, with retaining means for the reinforcing rods adjacent said supporting elements; such strip or bar being disposed substantially at right angles to the reinforcing rods and forming part of the reinforcement substantially at right angles to the same.

These and other features of my invention are more fully described hereinafter, reference being had to the accompanying drawings, in which:

Figure 1, is a plan view of a blank from which one type of supporting and spacing element within the scope of my invention may be formed; Fig. 2, is a perspective view illustrating a supporting and spacing member formed from the blank shown in Fig. 1; Figs. 3 and 4, are plan views illustrating other forms of blanks from which supporting and spacing elements within the scope of my invention may be made; Figs. 5 and 6, are perspective views illustrating modified forms of supporting and spacing elements within the scope of my invention made from the blanks shown in Figs. 3 and 4; Fig. 7, is a side elevation of the supporting member shown in Fig. 2, employed in a

slightly different manner; Fig. 8, is a plan view illustrating a further modification within the scope of my invention; and Fig. 9, is a view, similar to Fig. 7, showing a further modification within the scope of my invention.

The structure shown in Fig. 1, comprises a strip or bar of metal, a metal band for instance, indicated at 1, which may be, approximately, an inch, or an inch and one-eighth, or any other convenient dimension, in width, and approximately one-eighth or one-tenth of an inch, or any suitable proportion, in thickness; having one side cut as indicated by the lines 2 and 3, to form portions 4, which may be bent substantially upon the dotted lines 5, approximately at right angles to the strip 1, to provide supporting means. Simultaneously with the formation of the cuts 2 and 3 and the bending of the portions 4 to form the supporting means, corners 6 adjacent the cuts 2 of said main strip 1 are bent down as indicated, forming shoulders or hooked elements projecting slightly below the plane of the under surface of the strip 1, which shoulders or hooked elements serve to engage retaining means in the form of wires 7, extending across the strip 1, and over reinforcing rods 8, positioned over the supporting means 4. When thus arranged, the supporting and spacing members may be disposed approximately two feet between the centers, or at any other convenient or desired distance, while the reinforcing rods, mounted on top of said supporting and spacing members, may be spaced approximately six inches between centers, or at any other convenient or desired distance.

In Figs. 3, 4, 5, and 6, I have shown modified constructions in which the reinforcing rods are suspended from the supporting and spacing members. In Figs. 3 and 5, portions 4^a are cut from the strip 1 at opposite sides of the same, and in the cutting operation notches 9 may be formed in said strip adjacent the cuts 2^a to form hooked retaining elements, while said portions 4^a may be formed with projecting portions or shoulders 10. When wires 7^a are applied to clamp the reinforcing rods to the supporting and spacing members, the ends of said wires engage the notches 9 and are retained by the hooked elements against movement. The shouldered portions 10 directly underlie the wires 7^a so that if, in the assembly

of the reinforcing rods on the centering forms, the workmen walk upon the structure the reinforcing rods cannot be displaced or separated from the supporting and spacing means.

5 The construction illustrated in Figs. 4 and 6, is substantially the same as that illustrated in Figs. 3 and 5, excepting the position of notches 9^a in the strip 1, for retaining the ends of the wires 7^a.

10 If desired, only one of the portions 4 may be employed as the supporting means, as indicated in Fig. 7; the other portion indicated at 4^b, being bent over the reinforcing rod in the form of a hook to retain the latter in place. A further modification may consist in disposing portions 4^c cut from the strip 1 on opposite sides of the same, to form supporting and retaining means, as 15 indicated in Fig. 8. The corners 6^a in each instance being also bent down to provide hooked elements for retaining the wires 7 employed to confine the reinforcing rods in place.

20 25 In some instances it may be desirable to employ the supporting and spacing means in the manner illustrated in Fig. 7, but with the full value of the supporting legs 4, and in such instance I provide a structure of the type illustrated in Fig. 9, in which a retaining strap or hook 4^d for the reinforcing rod or bar is bent from the metal strip on the side opposite that from which the supports 4 are bent.

30 35 Although I have shown flat strips or bars of metal providing the supporting, spacing and reinforcing means, from which the integral supporting elements or legs may be pressed up, it will be understood that other 40 shapes may be employed, if desired; that is to say, angle or L-shaped sections, as well as T-sections. In the latter instance it is practicable to form the supporting elements or legs 4 alternately on opposite sides of the 45 central web, which is preferably disposed on the under side of such form or support.

50 55 While I have referred more particularly to the use of my improved supporting and spacing means in connection with reinforcing rods or bars employed in floor, ceiling and slab construction, it will be understood that it may be employed with equal value, ease, and facility, for supporting the reinforcing rods or bars used in wall or roof construction.

It will be understood, of course, that other modifications within the scope of my invention may be made, and my claims are intended to cover the same.

60 I claim:

1. A supporting and spacing means for reinforcing rods comprising a strip whose body portion is continuous in one plane having supporting portions displaced therefrom at 65 intervals whereby walls laterally disposed

with respect to the strip are formed in the body portion, and members engaging said walls and bridging said rods for confining the latter to said strip.

2. A supporting and spacing means for reinforcing rods comprising a flat strip whose body portion is continuous in one plane having portions displaced therefrom at intervals forming integral depending legs whereby walls are formed in the body portion of 70 said strip at an angle with respect thereto, and independent members engaging said walls and bridging said rods for confining the latter to said strip. 75

3. Supporting and spacing means for reinforcing rods comprising a strip of material having its edges notched, the portions displaced in providing such notches being bent downwardly to form integral legs and the notches having walls at right angles to 80 the length of the strip, and independent means for engaging the walls of said notches for confining reinforcing rods to said strip. 85

4. Supporting and spacing means for reinforcing rods comprising a strip of material 90 having its edges notched, the portions cut away to provide said notches being bent downwardly to form integral legs, and independent means for engaging the walls of 95 said notches for confining reinforcing rods to said strip, said legs being disposed directly below the reinforcing rods.

5. The combination of supporting, spacing and reinforcing means comprising a strip of metal having struck up portions 100 forming walls at an angle with respect to the strip, the material displaced depending from said strip in the form of integral legs, reinforcing rods or bars carried by said supporting and spacing means, said elements being 105 disposed substantially at right angles to each other and the supporting means being proportioned to afford a reinforcing value, and means engaging the walls adjacent the struck up portions for confining the elements 110 together. 115

6. The combination with supporting and spacing means for reinforcing rods comprising a strip of material having integral feet depending therefrom, said feet being formed 115 by displacing portions of said strip, a series of reinforcing rods, and independent retaining means for confining said rod to said strip of material, said retaining means engaging the walls of the openings formed by 120 displacing the portions forming the integral feet.

7. In supporting and spacing means for reinforcing rods, the combination of a metal strip disposed at right angles to said rods, 125 legs integrally connected to said strip, a reinforcing rod, a retaining wire for said rod, and hooked elements carried by the strip for confining said wire in position.

8. In supporting and spacing means for 130

reinforcing rods, the combination of a metal element disposed at right angles to said rods, legs integrally connected to said element, a reinforcing rod mounted on said element, a retaining wire for said rod, and downwardly projecting hooked elements carried by the metal element for engaging the ends of said wire to hold the same in position.

9. The combination, in reinforcing means for concrete construction, of a plurality of reinforcing rods extending in one direction, a plurality of metal elements disposed at right angles to said rods, integral supporting

members for said metal elements, the latter having shouldered projections adjacent the supporting members, and wire members having their ends caught by said shouldered projections for retaining said reinforcing rods to the metal elements.

In testimony whereof, I have signed my name to this specification, in the presence of two subscribing witnesses.

BARCLAY WHITE.
